UNITED STATES PATENT OFFICE.

WILLIAM A. LORENZ, OF HARTFORD, CONNECTICUT, ASSIGNOR TO UNITED STATES HAT MACHINERY CORPORATION, OF NEW YORK, N. Y., A CORPORATION OF VIRGINIA.

MACHINE FOR SHRINKING FELT ARTICLES.

Application filed June 25, 1923. Serial No. 647,587.

To all whom it may concern:

Be it known that I, WILLIAM A. LORENZ, a citizen of the United States, and a resident of Hartford, in the county of Hartford, 5 State of Connecticut, have invented certain new and useful Improvements in a Machine for Shrinking Felt Articles, of which the following is a specification.

This invention relates to machines for shrinking and felting hat bats and the like, and has particular reference to a machine of the sort having a belt (or belts) passing between a plurality of rolls and adapted to support the bats in unrolled condition, the 10 bats as they are carried by the belt between the rolls being kneaded, manipulated, or worked, and being maintained in a saturated condition, whereby the bats are felted and shrunk.

20 The aim of the present invention is to provide a machine of this sort having various features of novelty and advantage, and more particularly to provide an improved arrangement of belts; to provide the machine with means for preventing the bats from leaving the working face of the bat-carrying belt and winding themselves upon the rolls engaging said face, and to provide, in combination with the bat-carrying belt, 25 improved pressure rollers and deflecting rolls, which engage and operate upon the bats as the latter are carried forward by the belt.

30 Other objects of the invention are in part obvious and in part will be described more in detail hereinafter.

In the accompanying drawings, I have shown, by way of exemplification, one form or embodiment which the present invention 35 may take, but it is to be understood that this showing is merely illustrative and is not to be taken as restrictive of my conception, it being obvious that my improved machine is susceptible to various modifications and changes which would be within the spirit of the invention, without departing from the scope of the appended claims.

In these drawings;

Figure 1 is a top plan view of the machine, the pipes for delivering water onto the bat-carrying belt being omitted.

Fig. 2 is a diagrammatic showing of the

machine in vertical longitudinal section, this view being taken substantially on line 2—2 of Fig. 1.

Fig. 3 is a side elevation of the machine.

Figs. 4 and 5 are detail views showing diagrammatically the manner in which the waviness of the path which the bat-carrying belt is caused to follow, is determined.

Referring to the drawings in detail, the machine has a frame of any suitable construction, as for instance, a pair of side frames 10, tied together in any approved manner. Arranged circularly within the frame are a plurality of guide rolls between which suitable belts carry the bats in an unrolled condition and substantially in the path of the circle. In the present instance, these rolls are arranged in staggered 65 relation so that the path of the bats, while generally circular, is also wavy, resulting in the bats being progressively bent to and fro as they are passed through the machine. These guide rolls are here shown as consisting of a plurality of circularly arranged supporting rolls 11, constituting a circular trackway for one of the belts, and deflecting or wave rolls interposed between the supporting rolls. The deflecting rolls at the top of the machine are designated by 12, and those at the bottom of the machine by 12'. In the present illustrative disclosure 70 of the invention, these deflecting rolls are fixed against other than rotary movement in the frame, but it is evident that they may be made adjustable, if preferred. Running on the circular trackway provided by the supporting rolls 11, and deflected or waved, at intervals, by the deflecting rolls 12, is a 75 bat-carrying belt 13, which may be extended forwardly at the front of the machine, as at 14, so as to provide a bat-receiving portion, on which the bats are placed as they are fed into the machine. Passing between the supporting rolls 11 and the deflecting rolls 12' at the bottom of the machine is also a belt 15 which is in contact with, and travels at substantially the same speed as the other belt 13 on the lower or return run of the 80 latter. The working face, that is that face 85 against which the bats engage, of the belt 13, is provided with a multiplicity of knuckles which serve the purpose of manipu-

lating or kneading the bats at a very great number of points, thus greatly facilitating the felting and shrinking action.

In addition to the deflecting rolls 12, there are provided a plurality of pressure rollers which engage the working face of the belt 13 and the bats carried thereby. These pressure rollers are designated by 16, there being two pressure rollers associated with each supporting roll at the top of the machine, which means that there are two pressure rollers 16 between adjacent deflecting rolls 12, 12. The pressure rollers 16 are urged against the belt with the desired pressure in any suitable manner. For instance, they may be supported in the arms of levers 17, pivoted to the gudgeons 18, of the deflecting rolls, and the radially extending arms of the levers may be connected, in pairs, by tension springs 19.

The deflecting rolls 12 and the pressure rollers 16, which engage the working face of the belt 13 at the top of the machine, may be smooth but preferably they are provided with a multiplicity of projections similar to the knuckles or projections on the working face of the belt 13. These knuckles or projections are preferably elastic, and to this end, they may be formed of rubber. Also, by preference, they have a pyramidal shape.

The face of the belt 15, which co-operates with the belt 13 to carry the bats through the rolls at the bottom of the machine, is made smooth in the present instance. At the forward end of the machine, and immediately beneath the receiving portion 14 of the belt 13, the belt 15 is extended forwardly in order to provide a bat delivery position, from which the bats may be removed, after they have passed through the machine, and placed on the portion 14 of the knuckled belt. The extent of the deflection or wave imparted to the belt 13 as it passes between the supporting and deflecting rolls, may be varied or altered by changing the size of these rolls. If the bats are relatively thin or soft, they may be easily damaged and the degree of waviness in the belt should be less, and in this instance, the rolls should be relatively small, as shown in Fig. 5. In case the bats are stronger and therefore may be subjected to a more severe treatment, the rolls may be larger to increase the waviness of the belt, as shown in Fig. 4.

As the bats pass beneath the deflecting rolls 12 and the pressure rolls 16, they may have a tendency to leave the working face of the belt 13 and wrap themselves around these cylindrical members. In order to avoid this, I provide means for stripping, so to speak, the bats from the surfaces of the rolls 12 and rollers 16. In the present instance, these strippers are shown as being in the form of plates 20, having their inner,

or operative edges 21 adjacent to the belt 13, but sufficiently removed therefrom so as not to bear on the bats as they are carried beneath the strippers by the belt. These strippers extend, generally, longitudinally of the machine, and are spaced apart transversely thereof. In order to accommodate the strippers, the rolls 12, and the rollers 16 are formed in sections, between which the strippers are positioned, as is clearly shown in Fig. 1. The strippers 20 are suitably slotted so as to clear the shafts on which the sections of the rolls and rollers are mounted. Preferably, these strippers are removable, and to this end, they are carried by transversely extending rods 22, the ends of which are removably received by slots 23 in brackets 24 suitably secured to the upper portions of the side frames 10.

In order to facilitate the shrinking and felting operation of the bats, they are maintained in a saturated condition as they pass between the guide rolls at the top of the machine, and to this end, I provide above the machine, pipes 25, from which scalding hot water is sprinkled or sprayed on the working face of the belt 13 and on the bats carried thereby. In the present instance, water is not supplied to the bats as they are carried on the return or bottom path of the machine, except what passes downwardly at 25' between the belts.

The operation of the machine briefly, is as follows:

A bat, such as that indicated by B, is placed upon the receiving portion 14 of the belt 13, and this belt carries the bats beneath the deflecting rolls 12, and the pressure rollers 16. Since the belt is given a zigzag or wavy course, and the working face of the belt 13 and the rolls 12 and rollers 16 engaging thereagainst are provided with a multiplicity of kneading knuckles, the bats are manipulated and worked in such a manner that the fibers thereof are shrunken and felted together. The knuckles on the deflecting rolls 12 and the pressure rollers 16 greatly facilitate the felting operation. The strippers prevent the bats from leaving the working face of the belt 13 and winding themselves upon the rolls and rollers engaging thereagainst. After the bats have passed through the upper portion of the machine, they enter the bight between the belts 13 and 15, at 25', and are then carried between these belts in a zigzag course through the lower portion of the machine to the delivery position, to the position indicated by B'. The bat may then be removed by the operator from the delivery portion of the machine, and positioned on the receiving portion of the belt 13 and again carried through the machine.

I claim as my invention:

1. In a machine of the character de-

130

scribed, a plurality of generally circularly arranged supporting rolls forming a circular track-way, a bat carrying belt supported thereby for travel in a generally circular path, a second belt paired with the first one for a portion of the circular path of the latter, and cylindrical members having rolling contact with that portion of the operative face of said first belt not paired with said second belt.

2. In a machine of the character described, a plurality of generally circularly arranged supporting rolls and deflecting rolls therebetween, a bat carrying belt passing between said supporting rolls and deflecting rolls in a generally circular path, a second belt paired with the first one and passing between the supporting and deflecting rolls at the lower portion of the circular path, and pressure rollers bearing upon the operative face of said first belt at the upper portion of said path.

3. In a machine of the character described, a plurality of generally circularly arranged supporting rolls and deflecting rolls therebetween, a bat carrying belt passing between said supporting rolls and deflecting rolls in a generally circular path and having its operative face provided with a multiplicity of kneading knuckles, a second belt paired with the first one and passing between the supporting and deflecting rolls at the lower portion of the circular path, and pressure rollers bearing upon the operative face of said first belt at the upper portion of said path.

4. In a machine of the character described, a bat carrying belt having its working face provided with a multiplicity of kneading knuckles, rolls supporting said belt, and cylindrical members engaging the working face of said belt and having their peripheries provided with a multiplicity of knuckles.

45 5. In a machine of the character described, a bat carrying belt having its working face provided with a multiplicity of elastic kneading knuckles, supporting rolls therefor, and deflecting rolls between said supporting rolls and adapted to wave said belt, said deflecting rolls having their peripheries provided with a multiplicity of elastic kneading knuckles.

6. In a machine of the character described, a bat carrying belt having a multiplicity of kneading knuckles on its working face, rolls supporting said belt, and pressure rollers urged under pressure against the working face of said belt and having a multiplicity of kneading knuckles on their peripheries.

7. In a machine of the character described, a bat carrying belt provided with a multiplicity of kneading knuckles on its working face, supporting rolls for said belt,

deflecting rolls between said supporting rolls and adapted to wave said belt, pressure rollers between said deflecting rolls and urged under pressure against the operative face of said belt, said deflecting rolls 70 and said pressure rollers having a multiplicity of kneading knuckles on their peripheries.

8. In a machine of the character described, a travelling bat carrying belt, cylindrical members having rolling engagement with the bat carrying surface thereof, and means bridging the gaps between said cylindrical members for preventing the bats from leaving said belt.

15 9. In a machine of the character described, a bat carrying belt, cylindrical members engaging the bat carrying surface thereof, and means such, for example, as plates extending in the direction of travel 80 of said belt and spaced apart transversely of said belt for preventing the bats from leaving the face of said belt.

10. In a machine of the character described, a bat carrying belt, cylindrical 90 members engaging the bat carrying face thereof, and stationary plates having portions located between said cylindrical members and adjacent the bat carrying face of said belt for preventing the bats from leaving said face, said plates being transversely spaced apart and extending generally in the direction in which the belt is moved.

11. In a machine of the character described, a bat carrying belt, cylindrical members engaging the bat carrying face thereof, a plurality of longitudinally extending transversely spaced plates slotted to accommodate said members and each having one edge adjacent to but spaced slightly from the bat carrying face of said belt for preventing the bats from leaving said face.

12. In a machine of the character described, a bat carrying belt, cylindrical members engaging the bat carrying face thereof, a plurality of longitudinally extending transversely spaced plates slotted to accommodate said members and each having one edge adjacent to but spaced slightly from the bat carrying face of said belt for preventing the bats from leaving said face, and rods supporting said plates and removable from the machine.

13. In a machine of the character described, a series of circularly arranged supporting rolls, a bat carrying belt supported thereby, wave rolls between said supporting rolls engaging the bat carrying face of said belt, pressure rollers between said wave rolls also engaging the bat carrying face of said belt, said wave rolls and pressure rollers each having circumferential grooves at spaced intervals, plates positioned in said grooves and having their inner edges adjacent to but spaced from said belt to prevent

the bats from leaving the same, and removable rod supporting said plates.

14. In a machine of the character described, means for supporting and advancing a bat, cylindrical members adapted to engage the bat carried by said means, and means extending in the direction in which said bat is advanced and spaced transversely apart for preventing the bats from winding 10 up on said cylindrical members, said last mentioned means intersecting the peripheries of said cylindrical members.

15. In a machine of the character described, means for supporting and advancing a bat, cylindrical members adapted to engage the bat, and a plurality of longitudinally extending transversely spaced members slotted to accommodate said cylin-

drical members and each having an edge adjacent to but spaced slightly from said first 20 mentioned means for preventing the bats from leaving the latter.

16. In a machine of the character described, means for supporting and advancing a bat, cylindrical members adapted to engage the bat carried by said means, said cylindrical members having circumferential grooves at spaced intervals, and stripper members extending through said grooves and intersecting the peripheries of said 25 cylindrical members, said stripper members extending generally in the direction in which the bat is advanced and transversely spaced apart.

WILLIAM A. LORENZ.
